UNITED STATES PATENT OFFICE.

BENJAMIN BERNARD, OF NEW YORK, N. Y.

GARMENT.

1,123,224.

Specification of Letters Patent.

Patented Jan. 5, 1915.

Application filed December 13, 1913. Serial No. 306,418.

To all whom it may concern:

Be it known that I, BENJAMIN BERNARD, a citizen of the United States of America, residing at New York city, in the county 5 and State of New York, have invented certain new and useful Improvements in Garments, of which the following is a specification.

My invention relates generally to garments, and has especial reference to the articles known as coat fronts, which constitute the inner portion of a coat to give it 10 form and support.

Coat fronts are usually made of felt padding secured by numerous lines of stitching to two layers of stiff fabric, such as buckram, crash linen, or the like. The entire coat front is cut to the form of the garment in which it is to be used. In the 15 use of this kind of coat fronts, considerable difficulty and annoyance result from so-called "cockling," a term used to indicate the wrinkling and distortion to which such coat fronts are subjected after a very 20 short period of use.

The object of my invention is to provide a novel form of coat front which, while giving the desired form and support to the garment in which it is used, will not wrinkle 25 or lose its smoothness quite irrespective of the length of use. I accomplish this object, mainly, by securing the felt padding to a separate supporting layer of suitable material, and then by marginal stitching only 30 securing the padding and supporting layer to the fairly stiff inner fabric which lies immediately adjacent the coat lining.

An illustrative embodiment of the invention is shown in the accompanying drawing, 35 wherein—

Figure 1 is a front elevational view of the improved coat front; Fig. 2 is a rear elevational view thereof; and Fig. 3 is a horizontal sectional view on the line 3—3 of 40 Fig. 1.

Referring by reference characters to the several figures of the drawing, 10 denotes a suitably shaped pad of felt or other appropriate material, and 11 denotes a supporting

layer for the felt pad, the supporting layer 50 11 being made of crash or the like and of substantially the same shape and size as the pad 10. As shown particularly in Figs. 2 and 3, the pad 10 is secured to the supporting layer 11 by a plurality of lines of 55 stitches 12. At 13 I have indicated a strip of felt, attached to the pad 10, and which passes under the arm and up to the shoulder of the coat.

The pad 10 and its supporting layer 11 are suitably secured to the inner fabric 14, which is substantially of the shape and size of one half of the coat into which it is placed. The means for securing the pad to the inner layer 14 consists of a line of 60 stitching 15 which, as will be best seen from Figs. 1 and 3, is run at or about the margin only of the pad, but does not extend inwardly toward the body of the pad to any extent. In this way, while the pad is firmly 65 secured to the inner fabric 14, sufficient play or movement between these two parts is allowed to permit the pad to adjust itself to the proper shape without "cockling" i. e. 70 without becoming wrinkled or distorted. It 75 will be noted that the stitching 15 extends only along the two longer edges and the bottom edge of the pad 10 and supporting layer 11, and that the upper edges of these members are not secured to the inner layer 80 14. I have found by extensive trials, that by this construction I secure perfect smoothness of the garment, and eliminate all tendency of the coat front to "cockle".

What I claim is:—

A garment coat front, comprising a padding of a size and shape to extend from the top of the shoulder to a point in proximity to the waist line, a supporting fabric corresponding in size and shape to the padding 90 and engaging one side only of the latter, a plurality of lines of stitching connecting said padding and supporting fabric together, an inner fabric layer extending beyond the lower and one side edge of both 95 the padding and supporting fabric, said inner fabric layer being of the size and shape of one half of the entire front of the gar-

ment and adapted to face toward the wearer of the garment, the supporting fabric engaging said inner fabric, and stitching extending about the marginal portions only of said padding and said supporting fabric and connecting the same with said inner fabric.

In testimony whereof I have affixed my signature in presence of two witnesses.

BENJAMIN BERNARD.
